(57) **CLAIM**

The ornamental design for a cake serving and preserving utensil, as shown and described.

DESCRIPTION

FIG. 1 is a front perspective view of a cake serving and preserving utensil;

FIG. 2 is a back perspective view;

FIG. 3 is a front elevation view;

FIG. 4 is a back elevation view;

FIG. 5 is a right side elevation view;

FIG. 6 is a left side elevation view;

FIG. 7 is a top plan view;

FIG. 8 is a bottom plan view;

FIG. 9 is a perspective view of the utensil in use;

FIG. 10 is another perspective view of the utensil in use;

FIG. 11 is a perspective view of two utensils in use;

FIG. 12 is a front perspective view of a second embodiment of a cake serving and preserving utensil;

FIG. 13 is a back perspective view;

FIG. 14 is a front elevation view;

FIG. 15 is a back elevation view;

FIG. 16 is a right side elevation view;

FIG. 17 is a left side elevation view;

FIG. 18 is a top plan view;

FIG. 19 is a bottom plan view;

FIG. 20 is a perspective view of the utensil in use;

FIG. 21 is another perspective view of the utensil in use; and,

FIG. 22 is a perspective view of two utensils in use.

The broken line showing of a cake, cake plate, hands or knife in the drawings forms no part of the claimed design.

The break lines in the drawings indicate that the appearance of any portion of the cake serving and preserving utensil between the break lines forms no part of the claimed design.

1 Claim, 6 Drawing Sheets
